(57) **CLAIM**

The ornamental design for a razor travel case, as shown and described.

DESCRIPTION

FIG. 1 is a front perspective view of a razor travel case, according to an embodiment;

FIG. 2 is a front view of the razor travel case illustrated in FIG. 1;

FIG. 3 is a rear view of the razor travel case illustrated in FIG. 1;

FIG. 4 is a left side view of the razor travel case illustrated in FIG. 1;

FIG. 5 is a right side view of the razor travel case illustrated in FIG. 1;

FIG. 6 is a top view of the razor travel case illustrated in FIG. 1;

FIG. 7 is a bottom view of the razor travel case illustrated in FIG. 1;

FIG. 8 is a rear perspective view of the razor travel case illustrated in FIG. 1; and,

FIG. 9 is a front perspective view of the razor travel case of FIG. 1, shown in an example use configuration with a razor coupled thereto.

The broken lines in the figures illustrate portions of the razor travel case forming no part of the claimed design. In FIG. 9, the additional broken lines showing a razor coupled to the razor travel case illustrate environmental subject matter and form no part of the claimed design.

1 Claim, 9 Drawing Sheets
